SIDING MATERIAL

William W. Ford, Boston, Mass., assignor to The Patent and Licensing Corporation, Boston, Mass., a corporation of Massachusetts

Application March 15, 1932, Serial No. 598,961

8 Claims. (Cl. 20—5)

This invention relates to shingle strips and is more particularly concerned with strips suitable for siding, prepared from asphalt-saturated and coated fibrous material.

5 In the cutting of shingle strips from a parent sheet of roofing material it is of paramount importance that the strips be cut with minimum waste and that strips possessing the maximum coverage, consistent with safety, when laid in 10 overlapping courses, be cut from the minimum amount of material.

One of the objects of my invention is to provide a method of cutting shingle strips from a sheet so that a minimum amount of material is required 15 to cover a given area of wall structure when the strips are laid in overlapping courses.

Another object of my invention is to provide a shingle strip the area of which is unusually small as compared with shingle or siding strips as made 20 heretofore having the same amount of headlap and exposure.

A further object of my invention is to provide a strip which is not flimsy and will not easily tear during handling.

25 Further objects and advantages of my invention will be manifest from the following description in conjunction with the accompanying drawing of which;

Figure 1 is a plan view of a shingle strip made 30 in accordance with my invention;

Figure 2 is a plan view illustrating a method of cutting strips in accordance with my invention from a sheet of roofing material;

35 Figure 3 is a plan view of a plurality of strips made in accordance with my invention, laid in overlapping courses.

Referring to the drawing, the numeral 1 indicates a shingle strip having a plurality of tabs 2, separated by narrow slots or cut-outs 3, extending 40 along the lower edge of the strip. The upper edge of the strip is scalloped so as to form a series of alternate complementary extensions 4 and recesses 5. The strip is so designed that an extension occurs over each slot and also midway between adjacent slots. In the particular shingle shown in the drawing the tabs are rectangular in shape and the contour of the upper edge of the strip is a series of regular waves.

50 The upper or body portion 6 of the strip is preferably surfaced with fine mesh granular material, preferably of dark color, and the tabs are surfaced with coarser mesh granular material preferably red in color in order to simulate ordinary brick. The surfacing of coarse granular material

on the tabs extends to a line a small distance below the inner edges of the slots.

The strips may be made in various sizes, due 5 consideration being given to the production of strips which will cover the greatest surface area for the smallest amount of material and at the same time provide the necessary amount of safety and strength. With these considerations in view I have found a strip 36 inches in length having 10 an exposure of 3 inches and a headlap of $\frac{1}{2}$ inch to be satisfactory. The depths of the cut-outs will be 3 inches. The vertical distance from the inner edge of the cut-out to the line joining the innermost points of the recesses will be 1.5 inches and the vertical distance from the line joining 15 the innermost points of the recesses to the outermost point of the extensions will be 2 inches. Hence two rows of strips can be cut from a sheet 11 inches in width. Approximately 134 strips, 20 36 inches in length and having an exposure of 3 inches, are required to cover 1 square (100 square feet of surface). Therefore the amount of material measured in square feet necessary to cover a square when made into strips in accordance with 25 my invention will be—

$$\frac{11 \times 36}{144} \times \frac{134}{2} = 184.22 \text{ square feet.}$$

In comparison with this, siding strips having a straight upper edge which are made in 36 inch 30 lengths to be laid with a 3 inch exposure and $\frac{1}{2}$ inch headlap require—

$$\frac{6.5 \times 36}{144} \times 134 = 217.75 \text{ square feet.}$$

The saving effected by my strips is 33.53 square feet per square.

In addition to the large saving in material the strip is designed in such manner that it is not flimsy and subject to liability of tearing. Heretofore, various strips have been designed with the purpose in view of saving material. However, these strips have extensions above the tabs but not above the cut-outs or slots. If strips, 40 containing the amount of material which is present in strips made in accordance with my invention, were made with recesses instead of extensions opposite the slots, the distance from the inner edge of the cut-outs to the lowermost 45 points of the recesses would be only $1\frac{1}{2}$ inches, thereby making the strips extremely flimsy and subjecting them to liability of tearing during handling. In accordance with my invention this objectionable feature has been obviated by providing an extension above the cut-outs as well as 50 55

between the cut-outs so that the depth of the material above the cut-outs amounts to $3\frac{1}{2}$ inches.

In preparing the strips in accordance with my invention a sheet 10, of felted fibrous material is saturated and coated with asphalt and surfaced preferably with fine mesh granular material 11, of dark color. Longitudinal bands of asphalt coating are then applied to the marginal portions of the sheet. The bands are preferably of less width than the depth of the slots, the distance between the inner edge of the bands and that of the slots being substantially equal to the width of the slots. The bands are then surfaced with coarser mesh granular material of such color as to simulate brick. The sheet is then transversely slotted along the marginal portions so as to form two longitudinal rows 14, 15, the slots of one row being staggered in relation to those of the other. The slots may be cut in the sheet before applying the bands of coating. The sheet is then slit along a sinuous line 16, between the edges of the sheet, whereby adjacent strips having alternating complementary extensions and recesses are formed, and severed transversely along two longitudinal lines 17 connecting the inner edges of the cut-outs with the topmost point of the extensions, whereby to form the shingle strips. The lines 17 in one row are staggered in relation to the lines of the other row. As shown in the drawing the strips are severed so as to be formed with four tabs on each strip, but this number may vary. It is also apparent that any number of rows of strips which is a multiple of two can be formed from a sheet of appropriate width. Thus, for example, if it is desired to cut four rows of strips from a sheet 22 inches in width, a longitudinal band of double width would be applied along the median line of the sheet and bands of single width would be applied along the marginal portions; and transverse slots of double depth would be cut along the median line of the sheets and slots of single depth would be cut along the marginal edges. The sheet would be slit longitudinally on a straight line along the median and along a sinuous line between each longitudinal edge and the median line of the sheet so that the rows of strips adjacent to the median line are formed butt to butt and adjacent rows on either side of the median line are formed back to back. The adjacent rows on each side of the median line would be transversely severed into strips in the same manner as set forth in connection with Figure 2.

As shown in Figure 3 the strips are adapted to be laid in overlapping, horizontal courses in which the strips of one course are staggered in relation to those of adjacent courses. The strips are laid so that the bottom edges of the tabs of the strips in one course are coincident with the line joining the inner edges of the slots of the strips in the subjacent course thereby exposing narrow bands of dark colored surfacing which contrast with the color on the tabs or brick simulating areas thereby simulating horizontal mor-

tar joints 18. The surfacing on the body portion of subjacent strips is also exposed beneath the cut-outs of superjacent strips to simulate vertical mortar joints 19. The cut-outs of the overlapping strips overlie the extensions on subjacent strips. The dotted lines indicate the upper edges of the underlying strips and illustrate the manner in which the extensions of subjacent strips cooperate with the slots of the overlapping strips.

It is apparent that the tabs can be shaped other than rectangular and that the upper edge of the strip can be cut along zig-zag lines instead of a sinuous curve.

I claim as my invention:

1. A shingle strip having a plurality of tabs 15 separated by slots along one edge and a series of alternate extensions and recesses along the opposite edge, said extensions occurring opposite each slot and mid-point of each tab.

2. A shingle strip having a plurality of tabs 20 separated by recesses along one edge and a series of complementary extensions and recesses along the opposite edge, the contour of said last mentioned edge being an undulate curve, the crests of the curve occurring opposite each slot and mid- 25 way between adjacent slots.

3. A shingle strip having a plurality of rectangular shaped tabs separated by slots along one edge, the opposite edge having the contour of an undulate curve with alternate crests and troughs, 30 the crests of the curve occurring opposite the slots and mid-points of the tabs.

4. A shingle strip having a plurality of tabs along its weather edge and a series of substantially semi-circular projections and recesses alternating along the opposite edge, the number of said projections and the number of said recesses each exceeding the number of said tabs, the spacing between mid-points of adjacent tabs being twice that between the mid-points of adjacent 40 projections.

5. A shingle strip having a plurality of tabs defined by slots along its weather edge, and a series of substantially semi-circular projections and recesses alternating along its upper edge, one 45 said projection being opposite each slot and the mid-point of each tab.

6. A shingle strip having a plurality of tabs along its weather edge, the opposite edge of said strip having a contour of regular waves with a 50 wave-length substantially equal to half the distance between a point on any said tab and the corresponding point on the next adjacent tab.

7. A shingle having a plurality of tabs along its weather edge, the opposite edge of said strip 55 having a contour of regular waves, the mid-points of successive tabs being directly opposite the crests of alternate waves.

8. A shingle strip having a plurality of tabs along its weather edge and a plurality of tabs 60 along its upper edge, the spacing between mid-points of successive tabs on the weather edge being twice that between the mid-points of successive tabs on the upper edge.

WILLIAM W. FORD.
